Maurice E. Lawrence

UNITED STATES PATENT OFFICE.

SETH WHEELER, OF ALBANY, NEW YORK.

IMPROVEMENT IN LINKS FOR RAILWAY HORSE-POWERS.

Specification forming part of Letters Patent No. 38,778, dated June 2, 1863.

To all whom it may concern:

Be it known that I, SETH WHEELER, of the city of Albany, county of Albany, and State of New York, have invented a new and useful Mode of Constructing Links for Railway Horse-Powers; and I do hereby declare that the following is a full and exact description thereof, reference being had to the accompanying drawings and the letters of reference marked thereon, forming a part of this specification, like letters in the several figures indicating the same parts, and in which drawings—

Figure 1 is a perspective view of my improved link for railway horse-powers. Fig. 2 is a section thereof in line $\alpha\alpha$, Fig. 1. Fig. 3 is an inverted plan view of a portion of a chain and track or floor of a railway horse-power with my improved link applied thereto, and Fig. 4 is an end view of a portion of a railway horse-power chain and horse-track. (Shown in Fig. 3.)

Usually in constructing such power small shafts of wrought-iron are used extending from the link on one side of the chain to the link upon the other, the ends of the shafts being made to project beyond the links far enough to form the axles of the friction-rollers upon which the chains revolve. This plan, however, is objectionable, owing to the expense and weight of the shafts so used. As obviating such objection, a patent was granted to one Isaac R. Lawrence, October 11, 1859, for an improvement in railway horse-power chains, having the axles for the friction-rollers cast on and with the link, the axle and link being of the same cast metal. But this plan has also proved objectionable, inasmuch as it is almost impossible to cast the axles of such links perfectly true and uniform in size.

In my improved link, clearly shown in Fig. 1, the axle portions $a a$, which, whether made of steel, wrought-iron, or other suitable material, are first formed of the proper uniform diameter, then cut to a proper uniform length, and when the body portion b of the links are to be cast are inserted in the mold, whereupon the cast metal composing said portion b is poured around them.

Thus constructed, my improved link possesses the advantage of having its parts a and b firmly united together as at c , Fig. 2. The parts a are always of uniform diameter and length, and bear their proper relation to the part b for use in connection with the friction-rollers $d d$ and endless-chain links e and supporting-link f , or other device, as indicated in Fig. 3. Besides this, my improved connecting or axle link, as represented in Fig. 1, possesses this further advantage—to wit, that while its main portion b may be made of one variety of cast metal, its parts $a a$ may be composed of steel or such other variety of metal as is most suitable for bearings or axles for the friction-rollers $d d$. By my construction of axle-links I am therefore enabled, first, to utilize any tough material in place of cast-iron axles, which, from the constant jar they are subject to, are liable to break; second, I may use such metal as is most suitable for "bearings" or "journals" for the friction-rollers to revolve upon; and, third, I dispense with the cost and cumbersome weight of transverse shafts the ends of which have heretofore been made to form bearings for the friction-rollers, as before stated.

H in the figures indicates a lag or strip of wood, of which the track of the railway horse-power is composed, its ends being connected with the endless chains, as represented.

Having thus described my invention, what I claim as new, and desire to secure by Letters Patent of the United States, is—

1. The connecting-link $a b$, constructed as described, in combination with friction-rollers d , endless-chain links e , and lag H , substantially as and for the purpose described.
2. The use of a link which has a short hard-metal pin or journal and a cast-metal body united together in the act of casting, for the purpose set forth.

SETH WHEELER.
